FAUCET RECONDITIONING TOOL

Filed June 6, 1934

INVENTOR:
JESSE R. LAKE.
By Grover C. Hill,
Attorney.

UNITED STATES PATENT OFFICE

1,999,815

FAUCET RECONDITIONING TOOL

Jesse R. Lake, Detroit, Mich.

Application June 6, 1934, Serial No. 729,178

4 Claims. (Cl. 90—12.5)

It is a general known fact that faucets broadly speaking, are susceptible more or less to leakage, or continual dripping when they are supposed to be closed and completely stopping the flow of liquid therethrough. Customarily when the valve seat of the faucet is badly worn or otherwise deteriorated, even by turning the valve stem of the faucet as tightly as possible by the operator thereof, a leak can not be avoided due to the imperfect engagement of the stem with the seat thus indicated.

It is further known that there have been various attempts to correct this difficulty and apparently little or no progress has been made in this connection.

This invention seeks to and does positively overcome this difficulty by providing a small and compact tool with a series of cutters formed thereon so that by the simple operation of removing the stem from the faucet so affected and by inserting the tool directly into the faucet where the stem has been removed, and with the aid of the bonnet of the faucet, the tool is rotated gently by the operator, thereby recutting the valve seat. The tool is then removed and the faucet reassembled for use.

Another advantage of the invention is that the same provides a feature whereby it may be readily adjusted to practically any size of faucet as the valve seat therein is usually of a standardized dimension and proportion.

The invention possesses further advantages, which will become readily apparent during the course of the following detailed description, illustrated throughout the accompanying drawing, and more fully pointed out in the appended claims.

With reference to the drawing:

Figure 1 is a longitudinal section substantially twice size, of a typical faucet and showing the invention likewise enlarged and normally in the act of operation.

Figure 2 is an elevation of the complete invention, drawn to substantially full size.

Figure 3 is an enlarged section taken directly upon line 3—3 of Figure 2.

Figure 4 is an enlarged bottom view of the structure shown in Figure 2.

In the following description the invention proper will be distinguished by the customary reference numerals, while the various elements of the faucet will be designated by orderly letters of the alphabet.

The invention comprises elongated tubular shell 1 having square shank 2 formed upon the upper

end thereof, and said shank being adapted to detachably engage handle portion 3 as indicated.

Stem 4 is provided and is detachably positioned within shell 1 as clearly revealed in Figure 1. The upper end portion of said stem being provided with external threads 5 so as to accommodate nut 6 as indicated. The lower end portion of shell 1 is arranged so as to form cutting jaws 7 which are adapted to accurately conform to valve seat A of the faucet, and in Figure 4 it is seen that cutters 7 are preferably spaced at 120 degrees. The lower extremity of the shell is constructed to form a cutter pilot.

The lower end of stem 4 is arranged so as to form conically disposed expander 8, and elongated slots 9 within shell 1 render jaws 7 susceptible to expansion or closing by virtue of expander 8 of stem 4 for purpose of adjusting said jaws so as to be adapted to properly engage the valve seat upon which the cutting operation is to be performed.

An important feature is the method employed for aiding jaws 7 in the closing movement thereof for adjusting them from a larger proportion to a smaller proportion, and this method consisting of circumferentially formed recess 10 upon shell 1 where indicated and spring 11 coiled within said recess, and in this manner it is understood that the tension of said spring will perform the aiding movement as aforesaid.

The method employed for preventing turning of stem 4 as expander 8 is drawn upward for spreading cutters 7 for enlarging the cutting range of same, comprises lug 12 which is formed integral with said stem and is adapted to slidably engage one of slots 9 within shell 1 and permanently remain within said slot.

Sleeve 13 is provided and has funnel-shaped lower end 14 which is adapted to engage opening B within bonnet C of the faucet. It is also observed that a plurality of spaced apart grooves 15 are provided where shown upon shell 1 and in circumferential formation, and any one of said grooves being adapted to detachably receive spring 16. The purpose of sleeve 13, grooves 15 and spring 16 will be presently explained.

The details of construction of the invention having been completely set forth during the course of the several preceding paragraphs, the operation and advantage thereof follows:

The faucet D is dismantled by removing bonnet C with the original stem (not shown), and which expose the deteriorated valve seat A rendering the faucet ready for the cutting operation.

Sleeve 13 being slidably positioned upon shell

1, bonnet C is placed upon shell 1 and spring 16 is placed within one of grooves 15 upon said shell consistent with the height of the faucet to be reconditioned, and the funnel-shaped end 14 of 5 sleeve 13 being adapted to engage opening B of said bonnet, which is clearly seen in Figure 1. Handle portion 3 is placed upon shank 2 of shell 1 and nut 6 secured to threaded end 5 of stem 4. The tool as indicated is then inserted within faucet D and jaws 7 are adjusted to properly conform to valve seat A by means of nut 6. Of course it is understood that bonnet C has been inserted upon threads E of faucet D. In view of 10 spring 16 retaining sleeve 13 with funnel-shaped 15 end 14 thereof being taut with opening B of said bonnet handle portion 3 which is now made integral with the tool, is rotated sufficiently until seat A of the faucet will have been cut to a perfect state. The tool is then removed from the faucet 20 in the same manner as it was prepared and inserted therein, and the faucet reassembled for use.

An important feature of the invention is the 25 pressure feed effected for cutting jaws 7 as the tool is rotated with respect to valve seat A. This is accomplished by means of bonnet C of the faucet, which is readily apparent in Figure 1.

While I have herein set forth a single embodiment of the invention, the same would anticipate 30 certain minor changes in the details of construction thereof, if this condition should present itself during any probable further development for the market, however in any eventuality a departure from the general principle involved would be 35 consistently avoided.

Having thus described my invention, what I 40 claim as new is:—

1. In a faucet reseating tool, an elongated 45 tubular member provided with slots that extend upwardly from the lower end thereof, to form a plurality of legs, pilots formed on the lower extremities of the legs, cutter jaws formed on the lower portions of the legs, an actuating handle secured on the upper end of the tubular member for rotating the same, an elongated stem extending 50 through the tubular member and projecting beyond the respective ends thereof, means on the lower end of said stem for expanding the legs to radially adjust the cutter jaws, and means on the upper end of the stem for vertically adjusting the same.

2. In a faucet reseating tool, an elongated 55 tubular member provided with slots that extend

upwardly from the lower end thereof, to form a plurality of legs, pilots formed on the lower extremities of the legs, cutter jaws formed on the lower portions of the legs, an actuating handle secured on the upper end of the tubular member for rotating the same, an elongated stem extending 60 through the tubular member and projecting beyond the respective ends thereof, means on the lower end of said stem for expanding the legs to radially adjust the cutter jaws, the upper end 10 of the stem being threaded, a nut engaged therewith for vertically adjusting the stem when the nut is rotated, and means for preventing rotation of the stem in the tubular member while being vertically adjusted.

3. In a faucet reseating tool, an elongated tubular member provided with slots that extend upwardly from the lower end thereof, to form a plurality of legs, pilots formed on the lower extremities of the legs, cutter jaws formed on the lower 20 portions of the legs, an actuating handle secured on the upper end of the tubular member for rotating the same, an elongated stem extending through the tubular member and projecting beyond the respective ends thereof, means on the lower end of said stem for expanding the legs to radially adjust the cutter jaws, the upper end of the stem being threaded, a nut engaged therewith for vertically adjusting the stem when the nut is rotated, and means for preventing rotation of the stem in the tubular member while being vertically adjusted, 25 said last mentioned means comprising a laterally projecting lug formed on the stem and operable in one of said slots.

4. In a faucet reseating tool, an elongated tubular member formed with spaced slots that extend upwardly from the lower end of said tubular member to provide a series of legs, a pilot formed on the lower extremity of each leg, a cutter jaw formed on the lower end portion of each leg, a coil spring encircling the slotted tubular member above the cutter jaws to normally urge the latter inwardly, a stem extending longitudinally through the tubular member and projecting beyond the respective ends thereof, means on the lower end of said stem for expanding the legs and radially adjusting the cutter jaws, means on the upper end of the stem for vertically adjusting the same, additional means for preventing the rotation of the stem in the tubular member, 50 and a handle secured on the upper end of the tubular member for rotating the same.

JESSE R. LAKE.
